UNITED STATES PATENT OFFICE.

LOREN B. WALTERS AND KINSEY CADWALADER, OF GEORGETOWN, TEXAS.

WASHING-MACHINE.

SPECIFICATION forming part of Letters Patent No. 554,553, dated February 11, 1896.

Application filed January 15, 1895. Serial No. 535,002. (No model.)

To all whom it may concern:

Be it known that we, LOREN B. WALTERS and KINSEY CADWALADER, of Georgetown, in the county of Williamson and State of Texas, 5 have invented a new and useful Improvement in Washing-Machines, of which the following is a specification.

This invention is an improvement in washing-machines and seeks to provide, among 10 other improvements, a novel construction of casing and gear framing or support, an improvement in the clothes-receptacle and the devices for securing a circulation of water and steam through the clothes.

15 The invention has for further objects other improvements; and it consists in the novel constructions and combinations and arrangements of parts, as will be hereinafter described, and pointed out in the claims.

20 In the drawings, Figure 1 is a perspective view of the washing-machine, parts being broken away and others shown in section; and Fig. 2 is a sectional top plan view.

The body or suds-box A is made cylindrical in form and has below it a suitable furnace A', which is also preferably cylindrical, and the box is supported on legs B of gas- 25 pipe or similar tubing, bar or angle steel legs suitably secured to the box. Two of these 30 legs B are extended above the box and connected by jointed pipe connections with the bearing C, which supports the upper end of the shaft D, while one of said extended legs has an upwardly-projected stem b, slotted at b' so that the stud-axle b² can be adjusted vertically to take up any slack in the drive-chain E. The leg having the stem b also has a cross bar or section F below the slot b' and provided with bearings for the guide or idler 35 pulleys g under which the chain E is directed in its passage between the drive-wheel G on axle b² and the pinion G' on the shaft D. This forms a strong firm support for the gearing, which support is braced directly from 40 the floor or other foundation upon which the machine stands.

The clothes-holder H is located within the suds-box, is perforated, as shown, and is provided on its bottom with radial ribs H' and 45 at its center with a hollow center or tube I threaded internally, and upon such bottom

we form ribs or flutes J arranged radially and operating in a measure as a rubbing-surface.

Upon the inner side of the suds-box and 55 between the same and the clothes-holder we arrange inclined plates K extending up approximately to the top of the clothes-holder and operating to deliver the water over the upper edge of said clothes-holder and into the 60 same as it is revolved in the operation of washing.

The shaft D is threaded at its lower end corresponding to the shaft I, turns and engages therein and rests in a suitable step or 65

bearing on the bottom of the suds-box. If the operating devices be turned to the left or 70

in the opposite direction to that during wash- 75

ing, the clothes-basket will be caused to travel up the shaft D, so that it and its contents can 80

be adjusted above the water in the suds-box and so held in position for convenient hand- 85

ling. It is preferred to furnish means for 90

locking the clothes-holder in elevated position, a latch L being provided for such pur- 95

pose, and such latch L being preferably 100

supported on the hollow shaft I and engag- 105

ing a slot L' or similar seat on the shaft D, as 110

shown.

A rubber or beater M operates in the clothes- 115

holder and has a shank or handle N jointed 120

at one end at N' to the suds-box and support- 125

ing the beater M at its other or free end. 130

This beater is journaled to its hanger and has 135

upon its periphery ribs M', which by contact 140

with the clothes in the holder aid in cleans- 145

ing the same. This rubber M is hollow and 150

provided with a removable cap or plug M² 155

so it can be filled or partially filled with wa- 160

ter to secure the desired weight upon the 165

clothing.

In practice the clothing can be put into the machine with cold water and the latter gradu- 170

ally brought up to boiling-point, thereby 175

avoiding the setting or fixing of stains or 180

spots resulting from placing dry fabrics in 185

hot water.

The machine also requires but little water 190

comparatively, and the raising of the clothes- 195

holder affords convenient access to the cloth- 200

ing and avoids the necessity of clothes-sticks 205

and the like.

Having thus described our invention, what

we claim as new, and desire to secure by Letters Patent, is—

1. In a washing-machine the combination of the clothes-holder having a threaded center or tube and the shaft having a threaded engagement with said tube and a support for such shaft independent of the clothes-holder and devices by which to secure the drive-shaft and clothes-holder from independent turning substantially as set forth.
2. In a washing-machine the combination with the clothes-holder having a threaded

center or tube of the shaft having a threaded engagement with said tube whereby the clothes-holder may be caused to move along 15 said second shaft and a latch by which to lock said parts from independent movement substantially as set forth.

LOREN B. WALTERS.
KINSEY CADWALADER.
